Primary Examiner — Joseph Kukella

(57) **CLAIM**

The ornamental design for a building game with toy blocks, as shown and described.

DESCRIPTION

The patent or application file contains at least one drawing executed in color. Copies of this patent or patent application publication with color drawing(s) will be provided by the Office upon request and payment of the necessary fee.

1. Building game with toy blocks

1.1 : Top view of the building game with toy blocks

1.2 : Front or back view of a toy block for the building game

1.3 : Right or left view of a toy block for the building game

1.4 : Top or bottom view of a toy block for the building game

1.5 : Perspective view of a toy block for the building game

1.6 : Sample configuration of the building game

1.7 : Sample configuration of the building game

1.8 : Sample configuration of the building game

1.9 : Sample configuration of the building game

1.10 : Sample configuration of the building game

1.11 : Sample configuration of the building game

The ornamental design for a building game with toy blocks, as shown and described; reproduction 1.1 shows the building game including the toy block and other components; reproductions 1.2 to 1.5 show a toy block for the building game; reproductions 1.6 to 1.11 show sample configurations of the building game; the front view of the toy block is identical to the back view; the right view of the toy block is identical to the left view; the top view of the toy block is identical to the bottom view.
